ABSTRACT OF THE DISCLOSURE

A fastener base forming and attaching machine of a character including rotatable means which functions to form and subsequently attach such fastener bases to a support sheet.

The invention relates to improvements in forming and assembly machines and is particularly concerned with the novel method of and apparatus for forming sheet metal fastener bases and attaching them securely to sheet material.

File folders having prong fastener integrally attached thereto conventionally are fabricated by the introduction into an attaching machine of a completely formed prong fastener base. Such bases comprise an elongated body of strap metal having threading prongs on its ends which are bent perpendicular to the body. The body is formed on its longitudinal edges with longitudinally spaced tangs or lugs which also are bent normal to the plane of the base in the same direction as the prongs. When the base is attached to sheet material, these lugs pass through the material and are clinched to secure the fastener base thereto.

Supplying fastener bases with their prongs and lugs pre-formed is costly primarily in the fact that they assume more volume while in storage or in shipping, and are subject to being deformed prior to use. If the prongs or lugs are deformed at any time prior to being fed into an attaching machine they must be rejected. Also, the use of pre-formed fastener bases in automatic attaching machines renders it necessary to provide an excessively large feed magazine and for the machine to complete one operating cycle for each fastener base attached. This is costly and a time consuming procedure.

The present forming and assembling machine is of a character that receives fastener base blanks which can be packaged compactly and are not likely to become damaged prior to use. These blanks are fed into the machine from a magazine singly which then operates to bend the prongs and lugs perpendicular to the fastener base body and, during a half cycle of machine operation, deliver the formed fastener base into position where it is driven through the file folder or other sheet material and clinched thereto.

The resulting forming and attaching machine and feed magazine is compact and is inexpensive to operate and is capable of producing a larger number of finished file folders in a given operating period.

It is therefore an object of this invention to provide a novel forming and attaching machine of the character referred to.

Another object is to provide a novel machine for receiving fastener base blanks and forming the same prior to attaching them to sheet material.

Another object of the invention is to provide a machine of the character referred to which embodies novel feed and placement means for fastener base blanks.

Another object is to provide a novel feed wheel assembly.

Another object is to provide novel means to control cyclical rotation of a feed wheel assembly.

Another object is to provide a novel anvil assembly.

2

The structure and means by which the above noted and other objects and advantages of the invention are attained will be described in the following specification, taken in conjunction with the accompanying drawings, showing a preferred illustrative embodiment of the invention, in which:

FIG. 1 is a side elevational view of the machine.

FIG. 2 is a front elevational view thereof, omitting the feed magazine.

FIG. 3 is a vertical sectional view taken substantially along line 3—3 of FIG. 2.

FIG. 4 is an enlarged detail sectional view of the feed magazine and associated portion of the feed wheel assembly.

FIG. 5 is a transverse sectional view of the feed wheel assembly and associated ram, showing the parts in an initial position of operation.

FIG. 6 is a view similar to FIG. 5, showing the ram in the position assumed at the end of its initial down stroke.

FIG. 7 is a view similar to FIG. 5, showing the wheel assembly in position assumed following one-half cycle of rotation.

FIG. 8 is a view similar to FIG. 7, showing the ram depressed during the next cycle of operation, and showing a fastener base attached to sheet material.

FIG. 9 is an enlarged elevational view of the anvil assembly.

FIG. 10 is an end elevational view of the anvil assembly, showing parts broken away.

FIG. 11 is a vertical sectional view of the anvil assembly, taken substantially on line 11—11 of FIG. 10, showing parts in elevation.

FIG. 12 is an enlarged detail horizontal sectional view taken on line 12—12 of FIG. 11.

FIG. 13 is a perspective view of a fastener base blank.

FIG. 14 is a perspective view of a formed fastener base.

FIG. 15 is a perspective view of a fragment of sheet material, showing a fastener base attached thereto.

Referring to the exemplary disclosure in the accompanying drawings, the machine best shown in FIGS. 1 and 2, is comprised of a base plate 11 suitably supported on legs 12 and having spaced thereabove and integrally connected thereto as by means of spacer posts 13, an upper plate 14. The upper plate mounts a feed magazine 15 that houses a stack of fastener base blanks 16 to be successively fed to the attaching and forming apparatus to be described presently.

The fastener base blanks 16 each comprise, as best shown in FIG. 13, a thin sheet metal blank including a body portion 17 and prongs 18 that extend from the ends of the body portion. The longitudinal edges of the body portion are formed with attaching lugs 19. The prongs and lugs normally lie in the plane of the body portion. When formed, the lugs and prongs are bent normal to the body portion in the same direction as best shown in FIG. 14.

During machine operation the magazine 15 delivers one fastener base blank at a time to a rotatable wheel assembly 21. This wheel assembly includes a pair of axially spaced discs 22 suitably journaled for rotation in unison on a common axis in bearing journals 23 depending from the upper plate 14. The discs are held firmly spaced apart by a pair of parallel walls 24 extending between them and which are secured firmly to the discs. These walls are spaced apart a distance slightly greater than the width of a fastener base body portion 17 so as to provide a diametrical passageway or cavity 25 adapted to slidably receive the fastener base therebetween in a manner and by means to be described presently. Slidably mounted in the passageway 25 is a substantially rectangular spacer block 26 having firmly mounted therein a pair

of transverse pins 27. The said pins are of sufficient length to project through longitudinal slots 28 in the walls 24 so as to locate their end portions beyond the outside faces of said walls. In operation, the spacer block 26 is moved in the passageway 25 a distance determined by abutment of the pins 27 with resiliently mounted spacer block return plates 29. As best shown in FIG. 2, a pair of said plates 29 is mounted on the outside surface of each wall 24. These plates have mounting slots 31 therein to receive mounting screws 32 and the plates of each pair are urged toward each other by connecting springs 33.

As noted hereinabove, fastener base blanks 16 are fed one at a time to the rotatable wheel assembly. This is accomplished by a sweep action which sweeps the lowermost fastener base blank from the stack contained in the feed magazine. In order to accomplish this, the wheel assembly 21 is intermittently rotated one-half revolution in a clockwise direction. It is provided on the circumferential surface of each disc with a pair of diametrically opposed seats 34 (FIG. 4) one located in substantial alignment with each end of the passageway 25. As viewed in FIG. 4, when a seat advances beneath the magazine 15, during wheel assembly rotation, the bottom fastener base blank drops onto the seat and is carried with the wheel assembly against a stop block 15a and into a position of rest shown in FIG. 5, which is directly beneath ram 35.

The ram 35, which will be described presently in detail, then is carried downwardly into passageway 25 beyond the axial center of the wheel assembly and operates to force the body portion 17 of the fastener base blank downwardly into said passageway, all as illustrated in FIG. 6. Because the passageway has a size comparable to the dimensions of the body portion 17 only, the lugs 19 and prongs 18 are bent upwardly normal to the body portion 17. In forming the fastener base the spacer block 26 is pushed downwardly ahead of the fastener base and, as shown in FIG. 6, the pins 27 thereon strike against and depress the lower one of the spacer block return plates 29. When the ram is subsequently withdrawn, the depressed spacer block return plate 29 returns to its normal position and the spacer block is carried thereby upwardly a distance to locate its lower end substantially flush with the periphery of the discs 22.

The wheel assembly is now rotated in a manner to be described presently one-half revolution to carry the other seat 34 beneath the magazine and into alignment with the ram. This position is illustrated in FIG. 7 where it will be observed that the formed fastener base is now carried within the wheel assembly into the lower region thereof directly above an anvil assembly 36 to be described presently.

Rotation of the wheel assembly is effected by a constantly driven motor 37 (FIG. 2) operating through a trip clutch 38. Rotation is stopped at the half cycle by means of a retaining lever 39 (FIGS. 1 and 3) pivoted at 41 and having a ledge 42 that is intermittently carried into and out of the path of one or the other of a pair of diametrically opposed index pins 43 on said wheel assembly. The operation of this retaining lever 39 is effected through operation of the ram 35.

As best shown in FIG. 3, the ram is slidable in a vertical guide track 44. It has connected to it, as at 45, one end of a lever arm 46 pivoted at its other end to a standard 47. A crank arm 48 is connected to said lever intermediate its ends, as at 49. The crank arm is connected, as at 51, to an eccentric 52 that is intermittently rotated upon operation of the trip clutch 38, one complete revolution during each operating cycle. The crank arm has an extension 48a that depends freely through a slot 53 in the upper base plate 14, and which has a foot portion 54 that coacts with the retaining lever 49. The operation of the related parts is such that when the ram is being withdrawn upwardly from the wheel assembly after an operating stroke, the foot portion 54 is carried upwardly and in a

5 direction away from the retaining lever 39 and in so doing it engages with and wipes across a stud 55 said retaining lever 39 carrying said lever momentarily out from beneath an engaged index pin 43 thus permitting the wheel assembly to rotate clockwise one-half a revolution whereupon said lever 39 returns to its initial position and is engaged by the other index pin 43 to stop rotation of the wheel assembly.

10 Now, with the initially formed fastener base inverted and located directly over the anvil assembly 36, and a successive fastener base blank 16 seated on the wheel assembly beneath the ram, all as shown in FIG. 7, the cycle is repeated. That is, the ram 35 descends driving the fastener base blank down into passageway 25 and at 15 the same time the spacer block 26, which is forced downwardly thereby, drives the anvil aligned fastener base downwardly ejecting it from the wheel assembly 36. With a sheet of material 56 arranged over the anvil assembly, the fastener base prongs and lugs of the ejected fastener base will pass through said sheet into the position substantially as shown in FIG. 8.

15 It is to be noted that the lower edge of the depressed spacer block 26 passes out beyond the perimeter of the wheel assembly so as to insure that the fastener base is 20 thrust firmly against the anvil assembly which functions to splay the lugs outwardly and fold the prongs into the plane of the sheet material.

25 The anvil assembly 36 is best shown in FIGS. 9 through 12. It comprises a pair of upright rigid laterally spaced apart guide blocks 57 mounted firmly on a base 58. Said assembly is held firmly on the under side of the lower plate 11 as by screws 59. Mounted between said guide blocks is a die block 61 having its outside upper edges bevelled, as at 62, and suitably cut out at its ends to provide a pair of triangularly shaped end slots 63 having a wedge shaped body portion 64 between them. Mounted in each triangularly shaped slot 63 is a wedge block 65. The wedge blocks each have a pin 66 extended through them which pins project freely through angularly disposed slots 67 in the die block 61 and through horizontal slots 68 in the guide blocks 57.

30 Compression springs 69 arranged between the plate 58 and the bottom face of the die block 61 normally retain the die block in the elevated position shown in FIG. 10 and springs 71 in the guide blocks 57 urge the wedge blocks 65 inwardly towards each other so that their outside edges are substantially flush with the ends of said die block. When a fastener base is urged downwardly against the anvil assembly, its lugs 19 are initially 35 splayed outwardly against the bevelled edges of the die block and, as downward movement continues, the die block is depressed against the action of springs 69. The lugs are thus flattened out against the under surface of the sheet material by engagement with the top surfaces 40 of the guide blocks 57. When the die block 61 is depressed as aforesaid, the action of the pins 66 and angular slots 67 causes the wedge blocks 65 to move outwardly against the depending prongs 18 so as to bend them upwardly flat against the under surface of the 45 sheet material. Such attachment is shown in FIG. 11.

50 It should be quite evident that upon judicious arrangement of electrical controls, the trip clutch 38 may be actuated each time a piece of sheet material, such as a file folder, is positioned over the anvil assembly thus 55 the machine is entirely automatic in its operation.

55 Although I have described a preferred embodiment of my invention, in considerable detail, it will be understood that the description thereof is intended to be illustrative, rather than restrictive, as many details of the structure 60 disclosed may be modified or changed without departing from the spirit or scope of the invention. Accordingly, I do not desire to be restricted to the exact construction described.

65 I claim:

70 1. A fastener base forming and attaching machine

comprising a rotatable feed wheel assembly, means operable to position one fastener base on the circumferential surface of said feed wheel assembly, a normally retracted ram arranged normal to the axis of said feed wheel assembly operable to form and urge the fastener base into the interior of said feed wheel assembly, a spacer block in said feed wheel assembly displaced by said fastener base, means to normally retain the spacer block within the perimeter of the feed wheel assembly, a forming die external of and spaced from the periphery of said feed wheel assembly, said die being located in a position diametrically opposed to said ram, means operable to impart rotation to the feed wheel assembly when the ram is in retracted position, latch means operable to limit rotation to one-half revolution so as to locate the said fastener base in alignment with the die, said spacer block operating to project beyond the perimeter of the feed wheel assembly to eject the formed fastener base from the feed wheel assembly and into engagement with the die upon repeat operation of the ram, and means operably connected to the ram operating means operable to release said latch means when the ram is retracted.

2. A fastener base forming and attaching machine comprising a rotatable feed assembly having a cavity therein extending diametrically from one peripheral surface to the other surface of said rotatable feed assembly, means to feed one fastener base at a time into place over said cavity, a normally retracted ram located externally of said rotatable feed assembly operable to urge the fastener base into said cavity and to form attaching lugs

and prongs thereon, means to operate said ram, a die adjacent to the feed assembly diametrically opposed to said ram and adapted to have a sheet of material laid thereover, means operable to rotate said feed assembly, latch means operable to limit rotation of said rotatable feed assembly to 180° , means operable upon repeat operation of the ram to eject the formed fastener base from the cavity through the sheet material and into engagement with the die, and means operably connected to the ram operating means operable to release said latch means when the ram is retracted.

3. The machine recited in claim 2, in which spring controlled spacer block return plates are provided to retain the spacer block within the perimeter of the feed wheel assembly.
